United States Patent

Des. 236,300
Patented Aug. 19, 1975

236,300

PORTABLE SEAT

George J. Hartinger, 3906 Thomas Ave. N.,
Minneapolis, Minn. 55412

Continuation-in-part of design application Ser. No.
184,647, Sept. 28, 1971. This application July 20, 1973,
Ser. No. 381,156

Term of patent 14 years

Int. Cl. D6—01

U.S. Cl. D6—26

FIG. 1 is a side elevation of a portable seat showing my new design;

FIG. 2 is a top plan view thereof;

FIG. 3 is a rear elevation thereof;

FIG. 4 is a bottom plan view thereof;

FIG. 5 is a section on the line 5—5 of FIG. 1 and in the direction of the arrows;

FIG. 6 is a side elevation of an alternative bottom end design;

FIG. 7 is a top plan view thereof;

FIG. 8 is a rear elevation thereof;

FIG. 9 is a bottom plan view thereof; and

FIG. 10 is a section on the line 10—10 of FIG. 6 and in the direction of the arrows.

This application is a continuation-in-part of my copending application Ser. No. D. 184,647, filed Sept. 28, 1971.

I claim:

The ornamental design for a portable seat, substantially as shown.
